DESIGN FOR A WHEELBARROW

Gabriel C. Berker, Atherton, Calif.

Application October 23, 1946, Serial No. 134,187

Term of patent 3½ years

(Cl. D14—3)

To all whom it may concern:

Be it known that I, Gabriel C. Berker, a citizen of the United States of America, residing at Atherton, in the county of San Mateo and State of California, have invented a new, original, and ornamental Design for Wheelbarrows, of which the following is a specification, reference being had to the accompanying drawing, forming part thereof.

In the drawing:

Fig. 1 is a side elevation of a wheelbarrow, showing my new design;
Fig. 2 is a front elevation;
Fig. 3 is a top plan view;
Fig. 4 is a rear view; and
Fig. 5 is a bottom view of the same.

I claim:

The ornamental design for a wheelbarrow, substantially as shown.

GABRIEL C. BERKER.
